FAN BALANCING STAND

Harry R. Kincaid, Johnstown, Ohio, assignor to International Research and Development Corporation, Worthington, Ohio, a corporation of Ohio

Filed Apr. 26, 1966, Ser. No. 2,037

Term of patent 7 years

(Cl. D52—6)

The figure is a front perspective view of a fan balancing stand, showing my new design.

The rear and undisclosed side are substantially flat surfaces and unornamented.

I claim:

The ornamental design for a fan balancing stand, as shown and described.
